CLOSURE FOR CONTAINERS

Joseph H. Burnet, Glen Ridge, N. J.

Application February 8, 1941, Serial No. 378,025

4 Claims. (Cl. 220—27)

This invention relates to improvements in containers or cans for packing a flowable content for commercial distribution; and the invention has reference, more particularly, to a can or like container having a closure unitary therewith, so formed and constructed as to be easily opened by a tearing action without necessity for use of a can opener or other cutting or piercing instrumentality.

The invention has for an object to provide a novel container having at least its top end made of sheet metal of truncated conical form and so as to provide, in integral connection therewith, an end closure portion having a freely projecting peripheral flange, in connection with which closure portion and its flange is provided a separable tearing strip which may be easily manipulated, e. g., by a pair of ordinary pliers, pincers or other gripping means, to open the closure portion, thus avoiding necessity for the use of any cutting or piercing instrumentality.

This invention has for another object to provide a sheet metal container top having a novel form of end closure integral therewith, said end closure being provided with a separable tearing strip arranged in such novel relation thereto that, when torn open or away, not only will the container be opened for the discharge of its content therefrom, but in such manner as to provide convenient pouring spout means.

This invention has for a further object to provide a novel container closure which, after being opened, cannot be restored to its initial container closing relation, and consequently is adapted to render the container non-refillable for distribution use.

Other objects of this invention, not at this time more particularly enumerated, will be understood from the following detailed description of the same.

An illustrative embodiment of this invention is shown in the accompanying drawing, in which:

Fig. 1 is a side elevational view of a container having, unitary therewith, the novel closure means according to this invention; Fig. 2 is a top end plan view of the container with the closure means closed; Fig. 3 is a similar top end plan view showing the closure means open; Fig. 4 is a fragmentary vertical longitudinal sectional view, drawn on an enlarged scale, of the top end portion of the container with the closure means closed; Fig. 5 is a horizontal sectional view, taken on line 5—5 in Fig. 1, but drawn on an enlarged scale; Fig. 6 is a top end plan view of the container, drawn on an enlarged scale, and showing the closure means in process of being opened; and Fig. 7 is a fragmentary vertical longitudinal sectional view, taken on line 7—7 in Fig. 6.

Similar characters of reference are employed

in the above described views, to indicate corresponding parts.

Referring to the drawing, the invention is shown therein as embodied in an all metal can comprising a suitably shaped body 10 having bottom 11. Secured to the upper open end of the body 10, by a suitable interlocking seam 12, or in any suitable manner, is a top member 13. Said top member 13 is of hollow truncated conical shape, terminating at its free or top end in an integral closure portion comprising, an end or top wall 14, the marginal portion of which is folded upon itself to provide an underlying lap portion 15 which joins the conical wall of said top member, whereby said marginal portion of the end or top wall together with said lap portion 15 provides a freely outwardly projecting annular peripheral flange 16 as a part of the closure means, disposed in external overhanging relation to said top member wall. The closure means thus provided bridges the discharge opening 17 of said top member 13 which is defined by the upper truncated end portion of the latter, thus normally closing the same, and since the closure means is integral or continuous with said top member, the same likewise provides a closure of hermetical sealing character.

It will thus be seen that the top member and closure means comprises an integral structure formed from a single piece of sheet metal. That portion of the sheet metal piece which forms the closure means is scored by incised score lines to define a separable strip or section 18 to overlie the discharge opening 17, said strip or section 20 extending across the end or top wall 14 and around at least one margin thereof so as to terminate in the underlying lap portion 15. Preferably said separable strip or section 18 has its opposite end portions respectively extending around diametrically opposite marginal portions of the end or top wall so as to terminate in the underlying lap portion 15 at opposite points thereof, whereby the strip or section 18 may be wholly torn away and removed from the closure means. While this is preferable, it will nevertheless be understood, that said strip or section 18 may, if desired, be so defined by score lines as to terminate at one side only of the closure means and remain anchored or integrally joined with the latter by its other end, in which case the strip or section 18 may be torn open and folded back to expose the discharge opening 17, without entirely tearing the whole strip or section 18 away from the closure means.

The scoring which defines the separable strip or section 18 comprises, a pair of laterally spaced score lines 19 extending across the end or top wall 14 and around the margins thereof so as to join inwardly converging score lines 20 formed in the underlying lap portion 15. Said converg-

ing score lines 20 define a gripping lip portion 21 at one or both ends of the separable strip or section 18, which are initially integral with the lip portion 21 but which may be torn away therefrom when opening the container.

After the container body is filled with a desired content, the combined top member and closure means is applied to the upper open end of the filled container and operatively secured thereto, as, e. g., by the seam 12, thus closing and hermetically sealing the container.

When it is desired to open a filled container to discharge the content therefrom, the operator grips a lip portion 21 of the closure means and by an applied upward pulling force exerted upon an end of the separable strip or section 18 tears away the gripped end portion, and thereupon continues the tearing action so as to separate the strip or section, either to an extent sufficient to fold the same back and away from its initial overlying relation to the discharge opening 17 (see Figs. 6 and 7), or so as to tear the entire strip or section bodily away from the closure means (see Fig. 3). If the top member and closure means is made of relatively soft metal or other material, finger gripping by the operator may be sufficient to perform the operation. If the top member and closure means comprises a comparatively tough or resistant metal or the like, a sufficiently strong gripping of a lip portion 21 may be attained by the use of pliers, pincers or like instrumentality. It will be understood, however, that in neither case is it necessary to cut or pierce the material, as by use of a can opener or other cutting or piercing instrumentality.

When the container is opened in the manner described, it will be noticed that the removal of a lip portion 21 from the lap portion 15 of the closure means leaves a V-shaped gap 22 the apex of which is directed toward and terminates closely adjacent to the margin of the exposed discharge opening 17, thus providing a very convenient pouring spout for directing and confining the discharge stream of the substance, when the latter is poured from the container. Owing to the fact that the top member 13 of the container is of truncated conical shape terminating at the discharge opening 17, said top member provides a very convenient funnel-like means for directing the content of the container through the discharge opening and over the pouring spout formation when the container is inverted to discharge its content.

It will be obvious that once the closure means is opened by tearing open or away the separable strip or section 18, the closure is so mutilated that it cannot again be closed and sealed, and consequently unauthorized use of the container for commercial distribution of a substance cannot be successfully accomplished by refilling and closing the container.

It will be understood that the body 10 of the container may be made of sheet metal, or any other suitable sheet material. For example, for use in connection with some kinds of content, the body 10 may be made of paper or similar non-metallic material, having a bottom end of metal and a metallic top member and closure means; or the body may be made in other ways and of other kinds of materials.

Having now described my invention, I claim:

1. In a container, a body closed by a hollow substantially conical top member having its apex portion mushroomed into a substantially flattened closure member integrally unitary therewith, and having a two-ply freely projecting marginal flange portion exteriorly overhanging said top member, and said closure member having a separable section extending across the same, with at least one end thereof terminating in the under ply of said marginal flange portion, and said section being defined by weakening score lines having terminal portions which meet within the area of said under ply.
2. In a container, a body closed by a hollow top member of generally conical shape having its apex portion mushroomed into a substantially flattened closure member integrally unitary therewith, whereby said closure member is provided with a double freely projecting annular flange exteriorly overhanging the sides of said top member, and said closure member having a separable section extending across the same, with its opposite ends terminating in the underside of said annular flange, and said section being defined by laterally spaced weakening score lines, terminal portions of said score lines which extend into the underside of said annular flange converging in meeting relation within the confines thereof so as to define removable gripping lip portions therein and at the ends of said separable section.
3. In a container, a body closed by a hollow top member of suitable shape terminating in a discharge opening, said top member having, as a unitary integral part thereof, a closure means comprising an end wall bridging said discharge opening, marginal portions of said end wall being folded upon themselves to provide an underlying lap portion which joins the wall of said top member, thereby providing said closure means with a freely projecting marginal flange portion overhanging said top member wall, and said closure means having a separable section extending across its end wall above said discharge opening and around a margin of the end wall to terminate at one end in said lap portion, said separable section being defined by weakening score lines.
4. In a container, a body closed by a hollow top member of truncated generally conical shape terminating in a discharge opening, said top member having, as a unitary integral part thereof, a closure means comprising an end wall bridging said discharge opening, the marginal portions of said end wall being folded upon themselves to provide an underlying lap portion which joins the wall of said top member, thereby providing said closure means with a freely projecting annular peripheral flange overhanging said top member wall, and said closure means having a separable section extending across its end wall above said discharge opening and around opposite marginal portions of the end wall whereby end portions of said section terminate in said lap portion, said section being defined by laterally spaced weakening score lines, terminal portions of said score lines which extend through said lap portion converging one upon the other to meet adjacent to the margin of said discharge opening, whereby to define removable gripping lip portions at the ends of said separable section.

JOSEPH H. BURNET.
